UNITED STATES PATENT OFFICE.

JAMES W. CASTEEL, OF CEDARVILLE, KANSAS.

CHURN-POWER.

SPECIFICATION forming part of Letters Patent No. 358,334, dated February 22, 1887.
Application filed November 4, 1886. Serial No. 217,965. (No model.)

To all whom it may concern:

Be it known that I, JAMES W. CASTEEL, a citizen of the United States, residing at Cedarville, in the county of Smith and State of Kansas, have invented new and useful Improvements in Churn-Powers, of which the following is a specification.

This invention relates to churn-powers adapted to operate churning in which the dasher has a reciprocatory motion and will form a stand or support for the churn-body. The device is simple and compact in arrangement, durable, and not liable to get out of repair.

The improvement consists in the novel arrangement of the dasher connecting and operating parts, and particularly in the peculiar construction of the clamp for securing the dasher at any point to the vertically-reciprocating rod in such manner that the clamp will be secured to the dasher and to said vertically-reciprocating rod at one and the same operation, thus reducing the number of parts, lessening its cost, and greatly simplifying its construction.

Figure 1 is a perspective view of the device; Fig. 2, a sectional side elevation of the dasher connecting and operating parts; Fig. 3, a plan view of the dasher-connecting clamp, and Fig. 4 a sectional view of said clamp.

The frame of the device comprises the four corner-posts A, the base B, and the upper side bars, C, which unite the ends of the corner-posts. Two of the corner-posts are spanned near their upper ends by two pairs of braces, D and E, which are located at a distance apart. The braces of each pair are located on opposite sides of the posts, respectively, as shown, and form bearings for the shafts F and G. The shaft F is journaled in the upper braces,

D, and is provided on its outer portion with the gear-wheel H and the crank h. The shaft G is mounted in bearings in the lower braces, and has the pinion I keyed on its outer end and the crank or eccentric i keyed on its inner end. The pinion I meshes with the gear-wheel H, and receives motion therefrom. The vertically-reciprocating rod J is guided in its movements by the brackets K and L, secured at different levels to that side of the frame upon which the braces and gearing are located. The pitman M connects the crank or

eccentric i with said reciprocating rod. Motion is imparted from said rod J to the dasher-shaft N, which is held thereto by the clamp O, made in two parts, P and P', which are separable, and preferably hinged together at one end. The adjacent faces of the meeting parts are notched to form an opening when the parts are brought together for the passage of the rod J. That side of the clamp opposite the hinged side is held together by the clamp-bolt Q, passing through coincident openings in the ends of the parts P and P'. The front end of the clamp-bolt is hooked or bent, and extends across a notch, p, in the outer end of the part P of the clamp, and the inner end is threaded and receives the thumb-screw q. The end of the part P of the clamp has a groove, s, at right angles to the notch p, for the reception of the hooked end of the clamp-bolt, and preventing the same from accidental displacement. By tightening up the thumb-screw q the dasher-shaft N and reciprocating rod J will be bound together, and by slackening up or unscrewing the same the clamp can be adjusted to any position on said rod J, and the dasher-shaft N can be adjusted to any required point, and said positions of the rod, shaft, and clamp can be maintained by tightening the thumb-screw previously slackened.

The dasher-shaft can be readily detached by unscrewing the thumb-screw q sufficiently to allow the hook end of the clamp-bolt to be turned over, so as to disengage its hooked end from said shaft, as will be readily understood from said shaft, as will be readily understood from the dotted lines in Fig. 4.

One of the upper side bars, C, is hinged, to allow it to be turned up out of the way to permit access to the dasher-connecting clamp.

I claim—

1. The parts composing the churn-power, consisting of the upper shaft, its gear and crank, the lower shaft, its pinion and crank, the rod J, the pitman M, the dasher-shaft N, and the clamp O, adapted to be secured to the rods J N by the hooked screw a, the said operating parts being mounted upon the frame, and all combined substantially as described, for the purpose specified.

2. The herein shown and described clamp for connecting the churn-dasher-operating parts, consisting of two parts, P P', hinged

together at one end and having their meeting faces notched to form an opening, the clamp-bolt Q, passed through coincident openings in the opposite ends of the parts and having its outer end hooked and its inner end threaded, and the thumb-screw q, placed upon said inner threaded end, combined with the rods J M N, as shown and described.

In testimony whereof I have hereunto set my hand in the presence of three subscribing witnesses.

J. W. CASTEEL.
